UNITED STATES PATENT OFFICE

ANSON G. BETTS, OF TROY, NEW YORK.

PRODUCTION OF FERRIC SALTS.

969,833.

Specification of Letters Patent. Patented Sept. 13, 1910.

No Drawing.

Application filed January 7, 1909. Serial No. 471,120.

To all whom it may concern:

Be it known that I, ANSON G. BETTS, a citizen of the United States, residing at Troy, in the county of Rensselaer and State of New York, have invented certain new and useful Improvements in the Production of Ferric Salts, of which the following is a full, clear, and exact description.

This invention relates to the production of ferric salts and has for its chief object to provide a simple and efficient process for producing such salts by the electrolysis of ferrous salts of polybasic acids, for example ferrous sulfate and ferrous fluosilicate.

15 A further object is to provide a process for the purpose mentioned which can be practiced with apparatus of the simplest possible character.

In the production of such salts by electrolytic methods one of the chief difficulties encountered is polarization at the anode, with resulting loss of efficiency and destruction of the carbon anodes through increased resistance to the electrolyzing current, and in a prior patent granted to me November 7, 1905, No. 803,543, I have described a process in which the difficulty referred to is practically overcome by producing large relative movement between the anode and the electrolyte, so as to facilitate the continuous oxidation of the ferrous salt by the liberated anions. I have discovered, however, that satisfactory results can be obtained without such relative motion if the solution is electrolyzed at a high temperature. For example, if a solution of ferrous sulfate and sulfuric acid is electrolyzed at a temperature of from 50° to 100° C., using a carbon anode, the electrolysis proceeds without appreciable polarization at the anode and without evolution of gases, and a large percentage of the ferrous is converted into ferric salt, with very high current efficiency. Just what is the lowest temperature permissible depends on circumstances, such as current density at the anode and the percentage of acid and of ferrous iron in the solution. At temperatures of 50° C. and below I have not been able to oxidize iron successfully without keeping up a relative motion between the anode and the solution.

As a specific instance of the practice of my method I may give the following: A

55 solution containing 2.8 grams iron as ferric

sulfate, 1.6 grams iron as ferrous sulfate, 1.75 grams copper as copper sulfate, and about 4 grams free sulfuric acid per 100 cc., can be electrolyzed at a temperature of 86° C., with a graphite anode, at an anode current density of 11 amperes per square foot, without showing more than slight extra polarization beyond that necessary for the formation of ferric sulfate. The same solution at a temperature of 70° C., with a current density of 8.5 amperes per square foot, shows an extra polarization of half a volt or over, which is still greater at lower temperatures. With a current density of 14.5 amperes per square foot there is an extra polarization of over half a volt at 84° C., showing the necessity of using a still higher temperature at the higher current density. By circulating the electrolyte, or moving the anode, as described in my prior patent before referred to, a lower temperature may be used. In fact especially good results are obtained by employing considerable relative motion and some heat, the relative motion necessary being less as the temperature rises.

What I claim is:

1. The process of oxidizing in solution a ferrous salt of a polybasic acid to a ferric salt, which consists in electrolyzing the solution with an insoluble anode while maintaining the temperature of the said solution sufficiently high, as described, to substantially prevent the evolution of oxygen-containing gas at the anode, as set forth. 90

2. The process of oxidizing in solution a ferrous salt of a polybasic acid to a ferric salt, which consists in electrolyzing the solution with an insoluble anode while maintaining the said solution at a temperature higher than 50° C., as set forth. 95

3. The process of oxidizing in solution a ferrous salt of a polybasic acid to a ferric salt, which consists in electrolyzing the solution with an insoluble anode while maintaining the said solution at a temperature between 50° and 100° C., approximately, as set forth. 100

4. The process of oxidizing ferrous sulfate to ferric sulfate, which consists in electrolyzing a solution containing ferrous sulfate with an insoluble anode, at a temperature sufficiently high, as described, to substantially prevent the evolution of oxygen-containing gas at the anode, as set forth. 110

5. The process of oxidizing ferrous sulfate to ferric sulfate, which consists in electrolyzing a solution containing ferrous sulfate with an insoluble anode at a temperature between 50° and 100° C., as set forth.

6. The process of oxidizing ferrous sulfate to ferric sulfate, which consists in electrolyzing a solution containing ferrous sulfate, copper sulfate, and free sulfuric acid,

while maintaining the solution at a temperature between 50° and 100° C., as set forth. 10

In testimony whereof I affix my signature in the presence of two subscribing witnesses.

ANSON G. BETTS.
